(57) **CLAIM**

The ornamental design for a feeder, as shown and described.

DESCRIPTION

FIG. 1 is a top perspective view of a feeder, showing my new design;

FIG. 2 is a bottom perspective view thereof;

FIG. 3 is a front view thereof;

FIG. 4 is a rear view thereof;

FIG. 5 is its reduced left side view thereof;

FIG. 6 is its reduced right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 2; and,

FIG. 12 is an enlarged detail view of area 12 in FIG. 2.

The broken lines in the drawings illustrate the portions of the feeder, which form no part of the claimed design.

The dash-dot-dash broken lines encircling the enlarged views are for annotative purposes only and form no part of the claim thereof.

1 Claim, 12 Drawing Sheets
